UNITED STATES PATENT OFFICE.

CHARLES M. BURGESS, OF NEW BRITAIN, CONNECTICUT, ASSIGNOR TO THE RUSSELL & ERWIN MANUFACTURING COMPANY, OF SAME PLACE.

KNOB ATTACHMENT.

SPECIFICATION forming part of Letters Patent No. 503,450, dated August 15, 1893.

Application filed May 20, 1893. Serial No. 474,884. (No model.)

To all whom it may concern:

Be it known that I, CHARLES M. BURGESS, a citizen of the United States, residing at New Britain, in the county of Hartford and State of Connecticut, have invented certain new and useful Improvements in Knob Attachments, of which the following is a specification.

My invention relates to improvements in knob attachments, and the objects of my improvement are simplicity and economy in construction and convenience and efficiency of the article.

In the accompanying drawings: Figure 1 is a side elevation of a portion of a spindle and a knob having my attachment. Fig. 2 is an enlarged longitudinal section thereof. Fig. 3 is a plan view of the holding jaw and its collar. Fig. 4 is a face view of said collar. Fig. 5 is a longitudinal section of my attachment showing a slightly modified form, and Fig. 6 is a face view of the spring jaws for said modification.

A designates a knob having the usual central orifice for the spindle B and provided with a screw threaded shank 7, the end of which shank is beveled or countersunk as at 8, Fig. 2, upon one or more sides of its spindle hole. For convenience, I prefer to so bevel the end of the shank upon all sides of the spindle hole, as it can be done by means of a revolving tool, but when only one holding jaw is employed as in the construction first herein described, it is necessary to bevel the end of the shank upon one side only.

9 designates a collar which is provided with a square hole to fit the spindle B, and in its face I form the slot 10 to receive and hold one end of the holding jaw 11. This slot is preferably of a dovetailed form and made so narrow that the heel of the jaw will not fall through it into the spindle hole, while at the same time, the jaw is so loosely fitted in said slot as to have a swinging motion therein. The collar 9 is provided with a shoulder 12 and preferably with an annular groove 13.

C designates a sleeve designed to slip over the collar 9 and its holding jaw with one portion near its end engaging the shoulder 12 as shown in Fig. 2. The other end of this sleeve

is screw threaded and is screwed upon the shank 7 of the knob spindle. The sleeve is provided with devices for connecting it with a wrench or lever for rotating it, the same being illustrated in the form of a ridge 14 having angular faces for the application of a wrench. In order to prevent the collar 9 from being accidentally detached or displaced from the sleeve, I force a portion of the metal from the sleeve into the groove 13 of the collar 9, Fig. 2, as at 15 thereby permitting the sleeve to be rotated upon the collar, while at the same time they are held against longitudinal movement.

In use the parts are placed substantially as shown in Fig. 2 but without the sleeve being screwed up tightly. The knob is then slipped along on the spindle to the desired point, after which the sleeve is tightened up, thereby forcing the beveled face at the end of the knob against the beveled end of the jaw 11 causing the inner face of the jaw to be firmly pressed against one side face of the spindle for holding the knob in position. While I have shown only one jaw 11 and believe that the same will securely hold the knob in place, it is of course, evident that other like jaws may be added to the collar 9 on one or more of the several sides of its spindle hole as may be desired.

While I have thus far described a rigid jaw movably mounted on a collar, it is evident that substantially the same construction might be employed in connection with one or more spring jaws.

In Figs. 5 and 6, I have illustrated my improvement with spring jaws, the same being formed of a single piece of sheet metal bent into form. The base of these jaws is substantially of disk form with a central square hole for the spindle, said base 99 serving as a substitute for the collar 9 first described, and from this base the four spring jaws 110 are arranged to project toward the countersunk end of the knob shank. The operation is the same as before described, that is to say, screwing up the sleeve forces the ends of the jaws against the beveled faces at the end of the knob shank and thereby forces the jaws

against the sides of the spindle for holding the knob thereon. I claim as my invention—

The herein described knob attachment, consisting of the screw threaded knob shank having a beveled face at its end, the collar carrying a holding jaw, and the threaded sleeve

for forcing said jaw against the spindle, substantially as described and for the purpose specified.

CHAS. M. BURGESS.
